UNITED STATES PATENT OFFICE.

ALBERT G. ELVIN, OF PLANDOME, AND ADAM B. FAHNESTOCK, OF GREAT NECK,
NEW YORK, ASSIGNEES TO ELVIN MECHANICAL STOKER COMPANY, OF DOVER,
DELAWARE, A CORPORATION OF DELAWARE.

MECHANICAL STOKER.

1,381,977.

Specification of Letters Patent. Patented June 21, 1921.

Application filed October 4, 1920. Serial No. 414,634.

To all whom it may concern:

Be it known that we, ALBERT G. ELVIN, a citizen of the United States, residing at Plandome, in the county of Nassau and State 5 of New York, and ADAM B. FAHNESTOCK, a citizen of the United States, residing at Great Neck, in said county and State, have jointly invented a certain new and useful Improvement in Mechanical Stokers, of which im-

10 provement the following is a specification.

Our invention relates to appliances for mechanically conveying fuel from a supply receptacle to the firing opening of a locomotive or other steam boiler furnace, and sup- 15 plying it thereto as required to maintain combustion therein, and its object is to provide simple, effective, and reliable means for feeding fuel, at desired rate, to a crushing mechanism by which it is reduced to proper 20 size for firing, and thereafter delivering the fuel, in such condition, to the device by which it is projected into the boiler furnace.

The improvement claimed is hereinafter fully set forth.

25 In the accompanying drawings: Figure 1 is a view, partly in side elevation, and partly in vertical longitudinal central section, of the adjoining portions of a coupled locomotive and tender, illustrating an application 30 of our invention; Fig. 2, a partial plan or top view, on an enlarged scale, of the same; and Fig. 3, a partial vertical longitudinal central section, on a further enlarged scale, through the fuel feeder trough and the 35 crusher casing.

In the practice of our invention, referring descriptively to the specific embodiment thereof which is herein exemplified, a tender, indicated as a whole by A, and having a coal 40 bin or fuel receptacle, a, is coupled, in the ordinary manner, by a draw bar, C, to a locomotive, indicated as a whole by B, the firebox, b, of which is supplied with fuel from the coal bin of the tender, by a mechanical stoker, 45 the construction and manner of operation of which, so far as is necessary to clearly explain our invention, are as follows:

A longitudinally extending open topped fuel feeder trough or channel 1, the sides of 50 which are inwardly and downwardly inclined, is located below an opening, a', at the forward end of the coal bin, a, and a feeder bar, 2, is fitted to be reciprocated in the central portion of said trough. A pusher, 2^a, is

secured to the rear end of the feeder bar, and 55 said bar also carries a plurality of forwardly and upwardly inclined feeding plates, 2^b, which are alternated in position with a plurality of similarly inclined stationary feeding plates, 1^a, secured to the bottom of the 60 fuel feeder trough, each having a central opening through which the feeder bar passes freely.

A crusher casing, 3, into which the forward 65 end of the fuel feeder trough opens, is supported below said trough, the forward wall of said casing being formed by a vibratory crusher jaw, 4, which is curved eccentrically to a shaft, 4^a, upon which it is secured, and which is journaled in bearings below the 70 casing. The curved face of the crusher jaw, 4, is provided with a plurality of teeth, 4^c, which, in the movements of the jaw, work 75 between teeth, 3^a, on the inner wall of the crusher casing. The shaft, 4^a, of the vibratory crusher jaw, is swung about its axial line, by a motor, 5, the shaft, 5^a, of which is coupled, through suitable intermediate connections, which do not form part of our 80 present invention, and which include a universally jointed shaft, 5^b, a shaft, 5^c, gears, 5^d, 5^e, 5^f, 5^g, and a connecting rod, 5^h, coupled to a crank arm, 4^b, fixed on the shaft, 4^a.

Reciprocating movement, variable in degree, is imparted to the feeder bar and attached feeding plates, by the vibratory crusher jaw, 4, which carries, centrally at its upper side, an arm, 4^e, in which there is formed a curved recess, 4^d, which, in the rearward swing of the jaw, is adapted to engage 90 a correspondingly curved bearing, 2^c, at the front end of the feeder bar, 2, and impart rearward movement thereto. In the forward 95 swing of the crusher jaw, the arm, 4^e, abuts on a pin, 2^d, which is fitted to slide in slots, 2^f, formed in arms, 2^g, fixed to the feeder bar. A greater or lesser degree of traverse will be 100 imparted to the feeder bar by the crusher jaw, proportionately to the decrease or increase, respectively, of the distance between the axis of the pin, 2^d, and the bearing, 2^c, and when said pin is brought to the bottom of the slots, 2^f, no movement will be imparted to the feeder bar.

The adjustment of the pin, 2^d, in the slots, 105 is manually effected by movement of a latch, 6, journaled on the pin, and adapted to be engaged with any one of a plurality of teeth, 5^g.

2^b, which are formed in an inclined series, on the front end wall of the fuel feeder bar. When the latch stands below the lowest of the teeth, 2^b, the pin stands at the bottom 5 of the slots, and the distance between its axis and the bearing, 2^c, is so great that no movement will be imparted to the feeder bar in the vibratory movements of the crusher. When the latch is engaged with the upper- 10 most of the teeth, the maximum degree of traverse will be imparted to the feeder bar, and the traverse will be varied proportionately to the adjustment of the latch in the set of teeth. The pin, 2^a, is pressed up- 15 wardly in the slots by springs, 6^a, as permitted by the adjustments of the latch, and movement is imparted to the latch, to force the pin downwardly, against the tension of the springs, by a manually operated regulat- 20 ing rod, 6^b, coupled at one end to an arm, 6^c, on a rock shaft, 6^d, the opposite arm, 6^e, of which carries a roller, 6^f, working in a slot at the lower side of the latch. The regulat- 25 ing rod, 6^b, extends upwardly in the cab of the locomotive, and is connected to an eccentric, 6^g, working in a case, 6^h, and operated by a handle, 6ⁱ.

In the operation of a mechanical stoker in which our invention is applied, fuel drops 30 from the forward portion of the coal bin of the tender, into the subjacent fuel feeder trough, in which the feeder bar and attached fuel feeding plates are reciprocated, as hereinbefore described. At each forward move- 35 ment of the bar and plates, fuel which falls into the trough is pushed up and over the inclined faces of the fixed feeding plates, and in the rearward movement of the bar and its plates, a further supply of fuel drops 40 into the trough, and is similarly advanced at the next succeeding forward movement. The fuel which is thus moved forward, drops into the open top of the crusher casing, and it will be seen that the amount of fuel sup- 45 plied thereto will be controlled by the extent of the traverse of the feeder bar, which, as before described, may be varied or stopped, as required.

Such lumps of fuel as may be too large 50 to be properly fired will be held by the teeth at the bottom of the wall of the crusher casing, during the forward movement of the vibratory jaw, and by reason of the eccentricity of said jaw, will be crushed to proper size by said jaw in its rearward swing.

The fuel, as so fed and prepared, drops 55 from the crusher casing into the open top of a conveyer casing, 7, and is carried by a conveyer, 7^a, working therein, to the locomotive to be projected into the firing opening, 7^b, of the boiler firebox, 7. The conveying and fuel projecting mechanisms may be of any suitable known construction, and as they do not, in and of themselves, form 60 part of our present invention, they need not

herein be further described than to note that, in the application of our invention which is herein exemplified, the prepared fuel is delivered by the conveyer, 7^a, to an elevator casing, 8, in which charges of it are successively raised to the level of the firing opening by an elevator, 8^a, and delivered to two swinging fuel carrying and throwing shovels, 9, by which the charges of fuel are mechanically projected into the firebox, in 75 the manner of hand firing. The conveyer, elevator, and shovels, are actuated, in proper relation and sequence, by the motor, 5, through suitable known connections, which do not form part of our present invention, 80 and are not, therefore, herein described.

We claim as our invention and desire to secure by Letters Patent:

1. In a mechanical stoker, the combination of a fuel receptacle, having a bottom delivery opening; a feeder trough, located below said opening; a feeding appliance, adapted to be reciprocated in said feeder trough; a crusher casing, located below said feeder trough, and open at its top thereto; a movable crusher jaw, mounted in said casing; a subjacent conveyer, adapted to receive fuel from said casing, and deliver it, at a point adjacent to a steam boiler furnace; means for projecting the delivered fuel into the furnace; and a motor, actuating the feeding appliance and the crusher jaw.

2. In a mechanical stoker, the combination of a fuel receptacle, having a bottom delivery opening; a feeder trough, located below said opening; a feeding appliance adapted to be reciprocated in said feeder trough; manually adjustable means for regulating the degree of traverse of the feeding appliance; a crusher casing, located below the 105 feeder trough, and open at its top thereto; a movable crusher jaw, mounted in said casing; a subjacent conveyer, adapted to receive fuel from said casing, and deliver it at a point adjacent to a steam boiler furnace; means for projecting the delivered fuel into the furnace; and a motor, actuating the feeding appliance and the crusher jaw.

3. In a mechanical stoker, the combination of a fuel receptacle, having a bottom delivery opening; a feeder trough, located below said opening; a feeding appliance, adapted to be reciprocated in said feeder trough; a crusher casing, located below said feeder trough, and open at its top thereto; a movable crusher jaw mounted in said casing; manually regulable means for actuating the feeding appliance by the movements of the crusher jaw; a conveyer, adapted to receive fuel from the crusher casing, and deliver it 120 at a point adjacent to a steam boiler furnace; means for projecting the delivered fuel into the furnace; and a motor, actuating the crusher jaw.

4. In a mechanical stoker, the combination 130

of a fuel receptacle, having a bottom delivery opening; an open topped feeder trough, located below said opening; a plurality of inclined feeding plates, fixed transversely in 5 said trough; a feeder bar, adapted to be reciprocated in said trough; a plurality of inclined feeding plates, secured to said bar, and alternated in position with the fixed feeding plates; power actuated means for 10 reciprocating the feeder bar; a conveyer, adapted to receive fuel from the feeder trough, and deliver it at a point adjacent to a steam boiler furnace; and means for projecting the delivered fuel into the furnace. 15

5. In a mechanical stoker, the combination of a fuel receptacle, having a bottom delivery opening; an open topped feeder trough, located below said opening; a plurality of 20 inclined feeding plates, fixed transversely in said trough; a feeder bar, adapted to be reciprocated in said trough; a plurality of inclined feeding plates, secured to said bar, and alternated in position with the fixed 25 feeding plates; power actuated means for reciprocating the feeder bar; manually adjustable means for regulating the degree of traverse of said bar; a conveyer, adapted to receive fuel from the feeder trough and deliver it at a point adjacent to a steam boiler 30 furnace; and means for projecting the delivered fuel into the furnace.

6. In a mechanical stoker, the combination of a fuel receptacle, having a bottom delivery opening; a feeder trough, located below 35 said opening; a feeding appliance, adapted to be reciprocated in said feeder trough; a crusher casing, located below said feeder

trough, and open at its top thereto; a vibratory shaft, journaled in said casing; a crusher jaw, fixed on said shaft, and having its face eccentric thereto; a plurality of teeth on said eccentric face; a plurality of teeth on the opposite wall of the crusher casing, alternated in position with the teeth 45 of the jaw; a conveyer, located below, and adapted to receive fuel from, the crusher casing, and to deliver it at a point adjacent to a steam boiler furnace; means for projecting the delivered fuel into the furnace; 50 and a motor, actuating the feeding appliance and the crusher jaw.

7. In a mechanical stoker, the combination of a fuel receptacle, having a bottom delivery opening; a feeder trough, located below 55 said opening; a feeder bar, adapted to be reciprocated in said opening; a crusher casing, located below the feeder trough, and open at its top thereto; a vibratory crusher jaw, journaled in said casing; a bearing, 60 fixed on the feeder bar; a bearing, movable thereon, toward and from the fixed bearing; an arm on the crusher jaw, adapted to abut on one of said bearings in each direction of its traverse, and thereby to actuate the 65 feeder bar; manually operable means for varying the relation of the fixed to the movable bearing; means for delivering fuel from the crusher casing to a steam boiler furnace; and a motor actuating the crusher 70 jaw and said delivery means.
